UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

DESIGN FOR A COMBINED BUTTON-HOOK AND SHOE-HORN.

49,731.

Specification for Design.

Patented Oct. 3, 1916.

Application filed January 5, 1915. Serial No. 699. Term of patent 14 years.

To all whom it may concern:

Be it known that I, THOMAS HARDING, a citizen of the United States, residing at Newark, in the county of Essex and State of New Jersey, have invented a new, original, and ornamental Design for a Combined Button-Hook and Shoe-Horn, of which the following is a specification, reference being had to the accompanying drawing, forming part thereof.

Figure 1 is a side view of my combined button hook and shoe horn, and Fig. 2 is an edge view of the same.

I claim:

The ornamental design for a combined button hook and shoe horn, as shown.

THOMAS HARDING.

Witnesses:

JOHN T. MORLOCK,
CHAS. MUNTRICK.
